UNITED STATES PATENT OFFICE.

WILLIAM M. KELLY, OF NEW YORK, N. Y.

COMPRESSIBLE TYPE-JUSTIFYING SPACE AND METHOD OF MAKING THE SAME

1,130,826.

Specification of Letters Patent.

Patented Mar. 9, 1915.

Application filed March 13, 1912. Serial No. 683,611.

To all whom it may concern:

Be it known that I, WILLIAM M. KELLY, a citizen of the United States, residing at New York city, county of Kings, and State of New York, have invented certain new and useful Improvements in Compressible Type-Justifying Spaces and Methods of Making the Same, fully described and represented in the following specification and 10 the accompanying drawings, forming a part of the same.

This invention relates to compressible spaces for use in justifying lines of type by hand or machine.

15 The especial object of the invention is to provide a compressible space such that the adjacent type will be truly alined in setting, and the compression of the spaces in justifying shall not produce a distortion interfering with the proper position of the type.

Further objects of the invention are to secure these results in a space that takes a permanent set upon compression, so that the length of line may not subsequently 25 change because of any resiliency of the compressed spaces, to prevent molding material entering between the compressible spaces and type, and to provide a construction which shall be simple and cheap of 30 manufacture.

In the accompanying drawings forming a part of this specification, the invention is illustrated as embodied in its most complete and preferred form, and the construction 35 illustrated will now be described in detail and the features forming the invention then specifically pointed out in the claims.

In the drawings: Figure 1 is a perspective view of a rectangular non-compressible space forming the blank, from which my improved compressible space is formed in the preferred embodiment of the invention. Fig. 2 is a perspective view showing the same space after it has passed under the 40 forming die to produce the improved compressible space, and Fig. 3 is a vertical central section of the complete space in place between the type.

50 Referring to Figs. 1 and 2, the body of the space is shown at 10 and it will be seen that the action of the forming die upon the body has been to punch out two cylindrical bosses 11 and 12 upon one side of the space, the spacing faces of the bosses being in the 55 same plane and parallel with the side of the

space, and to form on the other side of the space two cylindrical cavities 13 and 14 (Fig. 3) resulting from the forcing and flow of the metal to form the respective bosses during the punching operation. Re- 60 ferring to Fig. 3, it will be noticed that the faces 11 and 12 on one side of the space and the surfaces 16, 17 and 18 on the other side form respectively two parallel planes against which the type *a* may squarely abut. 65

In justifying, when the line is being compressed to the desired length, the metal from the bosses flows back into the respective cavities from which it had been driven by the forming die and in this way the 70 lineal dimention of the space is decreased while at the same time the parallelism of the spacing surfaces remains undisturbed, and no distortion of the type occurs.

It will be noted that the compression 75 action is similar in many respects to the closing of a sectional telescope, this contraction of a body by its parts slipping upon one another being often described as a "telescopic" action. In the present instance, an almost purely shearing resistance is offered to compression, the movement under compression, however, being substantially similar to that of telescopic slides. The movement being almost wholly if not 80 entirely at right angles to the vertical plane of the space, and the material of the space being more or less plastic in its nature, the space offers a substantially uniform resistance to the compression force. 85

By the forming die a lip 15, 15 also is 90 preferably formed at each end of the space upon the same side as the bosses 11 and 12, and preferably tapers into a relatively thin and curved extremity as best shown in Fig. 95 3. This lip forms a sealing head to facilitate the making of electrotypes from the set-up matter. The space between the body 10 and the type *a* would ordinarily fill with molding material and prevent the easy removal of the mold. This is prevented by the lip 15 which extends, as shown, into contact with the type *a* thereby forming a sealing head which prevents further downward flow of the plastic material; the upper surface of the space, as indicated at 21, forming a comparatively smooth even bed from which the mold is readily removable. The taper given to the lip allows it to be compressed without undue distortion during the 100 105 110

justifying operation and to maintain the seal intact regardless of the extent of compression of the space.

While in the case chosen to illustrate the invention, a pair of cylindrical bosses with related cylindrical cavities are shown as disclosing one of its important features, it is obvious that the comparative size, or location, or form, or number of the spacing projections provided may be widely varied in practice without departing from the spirit of the invention, and this is also true of the particular form that may be given to the sealing lip described. I do not, therefore, limit myself to the particular form and arrangement of any of the parts as herein shown and described. It will be understood, also, that while the spacing projections are preferably formed by punching them from the body of the material, and this method forms a specific feature of the invention, they may be cast or otherwise formed, within the invention considered more broadly. The spaces may be made of any material suitable to secure the action desired. I have used lead with fair success, but prefer a slightly harder material and have secured the best results with a mixture of lead antimony and tin in about the proportions of eighty-eight parts lead, four parts antimony and eight parts tin. This is substantially the same as some type material and has the advantage in use that the spaces may be thrown into the melting pot with the type for remelting.

What is claimed is:—

1. A compressible space having a substantially rectangular body, and a plurality of cylindrical spacing projections located on one side of and compressible into the body, without any bending movement during compression and formed to offer a uniform resistance to the compression force.

2. A compressible space having a substantially rectangular body, a plurality of cylindrical projections located on one side of the body, and a plurality of related cylindrical cavities on the opposite side of the body, the said projections being adapted to enter the said cavities when the space is compressed, without any bending movement of the projections.

3. A compressible space compressing a substantially rectangular body and a plurality of lateral spacing projections carried by the body, the outer surface of said projections

being in a plane parallel with the opposite side of the body, and the projections being uniformly compressible into spaces within the body.

4. A compressible space having an inelastic and compressible sealing head whereby molding material is prevented from flowing between the said space and adjacent type.

5. A compressible space provided with a plurality of inelastic compressible bosses and an inelastic compressible lip adapted to form a sealing head between the space and adjacent type.

6. A compressible space comprising a body having compressible spacing projections punched therefrom without open rupture between the projections and body.

7. The method of producing compressible spaces, which consists in forcing portions of the body of the space outward to form spacing projections and cavities in the body into which the metal of the projections returns on compression, the changes in form taking place without open rupture between the projections and body.

8. The method of producing compressible spaces, which consists in forcing portions of the body of the space outward to form cylindrical spacing projections and cavities in the body into which the metal of the projections returns on compression, the changes in form taking place without open rupture between the projections and body.

9. In combination, the body 10, projections 11 and 12, and cavities 13 and 14, the projections being punched from the cavities without open rupture between the projections and body.

10. In combination, the body 10, projections 11 and 12, cavities 13 and 14, and the lip 15, the projections being punched from the cavities without open rupture between the projections and body.

11. A compressible space comprising a body having a plurality of spacing projections compressible into the body by a telescopic action.

In testimony whereof, I have hereunto set my hand, in the presence of two subscribing witnesses.

WILLIAM M. KELLY.
